UNITED STATES PATENT OFFICE

2,563,693

TABLE SERVICE SIGNAL DEVICE FOR
RESTAURANTSCharles G. Russell, Gallup, N. Mex., assignor of
twenty-five per cent to William A. Hawkins,
Gallup, N. Mex.

Application August 8, 1949, Serial No. 109,092

2 Claims. (Cl. 177—329)

1

This invention relates to a lamp and more particularly appertains to a service signal device for use in restaurants and similar establishments, the primary object of this invention being to enable a patron to noiselessly and quickly attract the attention of a waiter.

Another important object of this invention is to provide a service signal device for use in restaurants, which is so constructed that it is inconspicuous in appearance and easily blends with the restaurant surroundings.

These and ancillary objects and structural features of merit are attained by this invention, the preferred embodiments of which are set forth in the following description and illustrated in the accompanying drawings, wherein:

Figure 1 is a view in perspective of a conventional napkin holder, which constitutes the casing for this invention, which is shown in association therewith;

Figure 2 is a vertical sectional view taken on line 2—2 of Figure 1;

Figure 3 is a view in perspective of another type of housing for this invention;

Figure 4 is a vertical sectional view taken on line 4—4 of Figure 3; and

Figure 5 is a sectional view taken on line 5—5 of Figure 4.

Referring now to the accompanying drawings, attention is first directed to the embodiment illustrated in Figures 1 and 2. In this embodiment, the service signalling device is operatively associated with a conventionally constructed napkin holder, so that the signal device will be inconspicuous and yet will be prominently disposed. By employing the napkin holder 10 as a housing for the service signal device 12, the signal device is held in an upright, raised but inconspicuous position on the restaurant table. The napkin holder 10 includes a U-shaped body section 14 having a flat base or bottom wall 16 integrally formed between the ends of the opposing legs thereof. A pair of apertured end covers 18 and 20 are secured to the opposing side edges of the body section.

A partition or wall 22 is integrally formed between the opposing sides or legs of the body section and is spaced parallel with and above the base 16. A pair of upstanding follower members 24 and 26 are positioned on the partition 22 and retain a plurality of conventional napkins 28 in an upright position between the covers 18 and 20, the napkins being dispensed through the aperture in the central opening in the covers. It should be noted that the covers are friction-

2

ally held on the side edges of the body section and are detachable therefrom to enable a quantity of napkins to be stacked on the partition 22. A pair of insulating blocks 30 and 32 are secured to the under side of the partition 22 and a pair of U-shaped clips 34 and 36 are secured, as by rivets or the like, at their web portions to the under side of the insulation blocks, so that the clips extend downwardly from the central portions of the longitudinally spaced blocks. A pair of conventional dry-cell batteries 38 and 40 are clamped within and retained by the clips or clamps. An L-shaped contact member 42 is formed integrally with the clips 34 and 36, the longitudinal portion of the contact member being secured to the insulation blocks, so that the legs 44 and 46 extend downwardly at right angles from the outer end thereof and contact the outer end of the dry cell battery 38. Another contact member 46 is secured integrally with the partition 22 and extends downwardly therefrom to contact the outer end of the dry cell battery 40, the inner ends of the batteries abutting together. A conductor or lead wire 50 is secured to the inner end of the contact member 42 and is provided with an insulation covering 52. The conductor extends upwardly through a vertical tube 54 which is integrally formed at its lower end with the partition 22 and at its upper end with the web of the body section. An opening 56 is formed in the partition for the conductor, with the lower end of the tube concentrically disposed above the opening and an opening 58 is formed in the web of the body section, with the upper end of the tube concentrically disposed thereabove. A pair of springs 60 and 62 are riveted, as at 64, to the tube and bear against the follower members 24 and 26 to urge the same outwardly.

40 A tubular member or elongated sleeve 66 is slidably disposed within the tubular member 54 and is frictionally held therein for vertical adjustment. A stop plate 68 is integrally formed with the sleeve. A conventional switch 70 is 45 formed in the sleeve and a conductor is connected thereto and extends therefrom to a contact member 72 which is disposed through an insulating block 74 held within the upper end of the sleeve. The sleeve terminates in an axially 50 enlarged internally threaded socket 76, which receives a bulb 78 threadingly disposed in the socket in contact with the contact member 72.

Attention is now directed to Figures 3—5, where another embodiment of this invention is illustrated. In this respect, a vase 80 is formed with

a supporting base 82. A pair of U-shaped clamps 84 and 86 are formed integrally at their web portions with the under side of the base 82, the clamps supporting a pair of dry cell batteries 88 and 90. The clip 84 is formed with a forwardly projecting bar 92 which extends downwardly at one end of the battery 88 and is provided with a laterally extending arm 94 contacting, at its outer end, one end of the battery 90. A contact member 96 is formed integrally with the clamp 86 to contact the opposing end of the battery 90. A contact member 98 is operatively connected to the battery 88 and extends downwardly from the base 82. An insulated lead 100 is secured to the contact 98 and is connected, through a conventional switch 102, which is disposed in a sleeve 104 in the depending flange of the base. A tubular member 104 is disposed through an opening 106 formed in the bottom of the base and is retained therein by means of a locking nut structure 108. A complementary tubular member or elongated sleeve 110 is slidably disposed within the tubular member 104 and is locked in adjusted positions therein by means of a set screw 112, radially disposed through the side wall of the tubular member 104. The sleeve 110 terminates at its upper end in an axially enlarged socket 114, which receives a conventional bulb 116, similar to the construction of the socket 76 and its appurtenant bulb 78.

With respect to Figure 3, it is to be noted that flowers may be placed within the vase 80 and serve to encircle and camouflage the tubes, so that the service light 116 may be inconspicuously displayed on a restaurant table. Similarly, the service light, illustrated in Figures 1 and 2, is supported and operatively associated with the napkin holder so as to be inconspicuously displayed. All of the supporting structure and contact members for the dry cell batteries and the conductor line and the like are disposed within the napkin holder casing and within the base of the vase, so that they are completely hidden from view. Thus, the construction of the service light will enable such a light to be employed in order to attract the attention of a waiter for service and yet will not interfere with the interior design of a restaurant.

Of course, since many other modifications and purposes of this invention will become readily apparent to those skilled in the art upon a perusal of the foregoing description, it is to be understood that certain changes in style, size and components may be effected without a departure from the spirit of the invention and within the scope of the appended claims.

Having described the invention, what is claimed as new is:

1. A combined napkin dispenser and signal device comprising a housing, a bottom wall secured to said housing transversely disposed to and adjacent the lower edge of said housing, retaining clips integrally formed on the underside of said bottom wall and extending downwardly therefrom for receiving and retaining dry cell batteries, contact members associated with said clips and operatively connected to the batteries, a conductor operatively associated with said contact members, a tubular member secured at its lower end to said bottom wall and extending upwardly therefrom to house said conductor, an elongated sleeve slidably disposed in said tubular member, a socket member formed on the upper end of the sleeve to receive a light bulb, said conductor being connected to said socket, switch means operatively associated with said conductors, said housing having side walls, apertures in said side walls, and spring members secured to said tubular member adapted to urge napkins outwardly of said apertures.

2. A combined napkin dispenser and signal device comprising a housing, a bottom wall secured to said housing transversely disposed to and adjacent the lower edge of said housing, retaining clips integrally formed on the underside of said bottom wall and extending downwardly therefrom for receiving and retaining dry cell batteries, contact members associated with said clips and operatively connected to the batteries, a conductor operatively associated with said contact members, a tubular member secured at its lower end to said bottom wall and extending upwardly therefrom to house said conductor, an elongated sleeve slidably disposed in said tubular member, a socket member formed on the upper end of the sleeve to receive a light bulb, said conductor being connected to said socket, switch means operatively associated with said conductors, said housing having side walls, apertures in said side walls, spring members secured to said tubular member adapted to urge napkins outwardly of said apertures, an insulated block disposed in the upper end of the sleeve below the socket section and a contact member vertically disposed in said insulated block.
